UNITED STATES PATENT OFFICE.

LUCIUS HARLOW AND GUSTAVUS PARKER, OF HOLYOKE, MASS.

MECHANISM FOR LAYING OFF SHEETS FROM A PAPER-CUTTER.

SPECIFICATION forming part of Letters Patent No. 313,864, dated March 17, 1885.

Application filed August 28, 1882. (Model.)

To all whom it may concern:

Be it known that we, LUCIUS HARLOW and GUSTAVUS PARKER, both of Holyoke, Hampden county, Massachusetts, have invented a new and useful Improvement in Mechanisms for Laying off Sheets from a Paper-Cutter, of which the following is a specification, reference being had to the accompanying drawings, which are hereby made part thereof.

This invention has relation to improved means for receiving paper in sheet form from mechanism adapted to manipulate said paper while in a web form, and to sever said web into sheets, so that the mechanism herein described may receive, conduct, and lay off the sheets one by one upon each other in a uniform regular pile; and the invention consists in certain features of construction hereinafter described, and specifically set forth in the claims.

Referring to the drawings, Figure 1 is a side elevation of a paper-piling machine constructed in accordance with our invention. Fig. 2 is a substantially central vertical section of Fig. 1. Figs. 3 and 4 are details of detached portions, the former being a perspective view of the under side of the gripping mechanism.

Like letters indicate like parts in all the figures.

A A represent rotary transverse cutters of usual construction, to which a web of paper is guided by any suitable means from any mechanism—such as the drying-rolls of a Fourdrinier machine—and by which said web is severed into sheets of a length equal to the circumference of one of the rolls. If desired, any well-known reciprocating or other transverse cutting mechanism may be substituted for the rolls A A, the requisite being that the web shall be severed into sheets of desired length and the leading end of each sheet be delivered to and between the tapes B B'. The tapes B are arranged about a driving-roll, C, and guide-rolls B', B², B³, B⁴, B⁵, and B⁶, and against roll B¹¹. The tapes B' are arranged about the roll C, B', B², B³ B⁸, B⁹, B¹⁰, and B¹¹, so that the sheets are passed from the rolls A between the lower one thereof and the roll B⁶ into the bite of the tapes, which occurs at the roll B¹¹, and from thence (between the tapes) about the driving-roll C, which gives motion to both series of tapes over the roll B' downward and

beneath the roll B², upward and over the roll B³, and from thence downward to and between the rolls B⁴ B⁸ into a wedge-shaped guide or chute, D.

It is understood, of course, as is usual in tape-guiding mechanism, that there are two series of endless tapes arranged about the rolls, as described, and each series comprises two or more of said tapes, arranged parallel with each other upon the rolls, the upper and lower series, B and B', being arranged to run in contact with each other during a portion of their course—namely, that portion taken by the paper, as described. Within the frame-work E, which supports these rolls, may be arranged two sliding blocks, E' E'', which serve as bearings for the rolls B², B³, and B⁵, which blocks are also connected with adjusting-screws E³ E⁴ in such manner that the blocks and the rolls mounted thereon may be moved toward and from each other for the purpose of regulating the tension of the tapes. For instance, by raising the block E' the series of tapes B are tightened, and by lowering the block E'' the series of tapes B' are tightened, and in each of these movements of the separate blocks both series are in a measure affected in their tension—that is to say, if the block E' alone be lowered both series of tapes are tightened.

As is usual, the cutters A are geared to each other, and in order to give the same surface speed or motion to the tapes the roll C is provided with a gear, C', which meshes with the intermediate gear, C², and this with another intermediate gear, C³, which meshes with the gear on the lower cutting-roll, and said roll C is thus made to positively revolve and give motion to the tapes. (See dotted lines, Fig. 2.)

F represents the receiving-table upon which the severed sheets are piled, and it is mounted upon four vertical screws, F', one at or near each corner of the table. These screws are mounted upon beams F'', which constitute the frame-work of the table. Each of the screws F' (see Fig. 4) is provided with a pinion, F³, which is adapted to mesh with a worm, F⁴, mounted upon a shaft, F⁵, running along the side of the frame-work. A similar shaft is arranged on the opposite side of the table, and a counter-shaft, F⁶, provided with bevel-gears F⁷, which mesh with similar gears, F⁸, arranged on the worm-shafts F⁵, is extended

from side to side of the machine, so that when motion is given to said counter-shaft it is conveyed to both of the worm-shafts F^5 and to the screws F' , in order that the table F may be gradually depressed in position in proportion to the quantity of paper laid thereon, such depression being intermittently produced by means of a ratchet, G , mounted upon the shaft F^6 and operated by a pawl, G' , (see Fig. 1,) 5 pivotally secured to an oscillating lever, G^2 , which is pivotally mounted upon the framework E , as at G^3 , and which is oscillated upon its pivot by means of a connecting-rod, G^4 , connected with the disk G^5 , mounted upon the 10 shaft of the lower cutting-roll A , so that at each revolution the pawl G' is made to take a tooth in the ratchet G and to revolve the ratchet and the shaft F^6 , with its gears F^7 , the intermeshing gears F^8 , and the worm-shafts 15 and screws a distance depending upon the distance apart of the teeth of the ratchet G . It is apparent that in the revolution of the disk G^5 the pawl is advanced a certain distance over the ratchet, and is returned a like distance when it revolves the ratchet. 20

The upper end of the lever G^2 is provided with a connecting-rod, H , and this rod is pivotally secured to a swinging frame, H' , depending from a shaft, H^2 , pivoted in standards H^3 , 25 secured at opposite sides of the table.

The lower ends of the frame H' terminate in rods H^4 , which work loosely in slots or openings passing vertically through a reciprocating gripper-bar, I .

35 At each side of the frame-work of the table portion of the machine, and extending from end to end thereof, is arranged a guide-rod, I' , upon which the gripper-bar slides. These guide-rods are arranged parallel with the surface of the table. The gripper-bar is provided with grippers I^2 , which project from a rock-shaft, I^3 , mounted in bearings I^4 , secured to the lower surface of the bar I . A coiled spring, I^5 , has one end secured to the shaft, and the 40 opposite end secured to the lower surface of the bar, in order that when the grippers I^2 are separated from the lower surface of the bar by partially rotating the shaft I^3 said spring may be the means for automatically returning 45 the grippers to a position of contact with the bar. The means for opening and closing the grippers comprise two arms, I^6 I^7 , projecting from the shaft I^3 at substantially a right angle to each other, the former being projected 50 vertically and downwardly from the shaft. In the movement of the gripper-bar I toward the receiving end of the table—that is, toward the guide-chute D —the arm I^6 comes in contact with a latch, J , (see Fig. 2,) pivoted at J' to a

55 fixed part of the frame-work, and having an extension, J^2 , which prevents a movement of the portion J toward the chute D , the construction being such, however, as to permit a movement of said portion J in a direction from 60 the receiving-chute, so that as the gripper-bar approaches the receiving-chute the arm I^6 comes in contact with the portion J , and the

gripper-shaft is thereby oscillated, and the grippers removed from contact with the gripper-bar, and against the tension of the spring I^6 , so as to be open and in condition to seize 70 the leading end of the sheet as it is projected through the chute. In passing completely over the latch J the spring quickly closes the grippers upon the sheet, whereby it is retained by the gripper-bar. Depending from the cross-shaft K , in the swinging frame H' , is a rod, K' , which passes through a slot formed in the edge of the gripper-bar, and projects below said bar, so that when the grippers close upon the sheet the lower portion of 75 said rod K' is in front of the edge of the sheet held by the grippers. From the same shaft, K , is a second rod, K^2 , which projects at a different angle from the shaft than does the rod K' , and so as to come in contact with the lever 80 L , which projects from the gripper-shaft I^3 . As the gripper-bar approaches the end of the table opposite the chute D , the arm I^7 rides the incline of a cam, M , fixed to the framework, so that the shaft I^3 is oscillated against 85 the tension of the spring to open the grippers I^2 . As the bar I finishes its movement, the rod K' through gravity remains stationary, and, being against the edge of the sheet, positively 90 prevents a retention of the sheet between the grippers and the gripper-bar. At the commencement of the return movement of the bar the lever L comes in contact with the arm K^2 , and moves the rod K' a short distance in the 95 opposite direction to that in which the bar is moving, so as to completely lay the end of the sheet which has just been delivered from the grippers. In this instance we have shown but a single rod K' , and it is clear that two or more 100 may be used for the efficient delivery and laying of the leading end of the sheet.

To lay the tail end of the sheet, we make use of the pivoted rod N , which has a slanted portion, N' , that comes in contact with the upper 110 surface of the gripper-bar, so that as the bar approaches the guide D said lever is raised, and as the bar recedes from the guide said lever falls by gravity upon the tail portion of the sheet, and holds it in position while the 115 leading end is being delivered and laid.

Having described our invention, what we claim is—

1. The combination, with web-severing mechanism as described, of a series of guiding-tapes, a guide-chute, a receiving-table mounted upon vertical screws, means, as described, for operating said screws, a gripper-bar constructed to reciprocate over the table, and means, substantially as described, for 120 opening and closing the grippers at the end of each reciprocation of the gripper-bar, substantially as shown and described.

2. The combination, with a reciprocating gripper-bar carrying an oscillating gripper-shaft provided with a projecting lever, of a rock-shaft having a depending rod passing through the gripper-bar, and a projecting arm arranged to be operated by the lever of the gripp-

per-shaft, whereby a positive ejection of the leading end of the sheet from the gripper is secured, substantially as shown and described.

3. The combination of the swinging frame H', the gripper-bar I, the gripper-shaft I³, having the arms I⁶ I⁷, the cam M, the pivoted latch J, the connecting-rod H, the lever G², the pawl G', the disk G⁵, connecting-rod G⁴, the ratchet G, the counter-shaft F⁶, provided with bevel-gears F⁷, the worm-shafts F⁵, provided with bevel-gears F⁸, the gear-screws F⁹, and the table F, substantially as shown and described.

4. The combination of the swinging frame H', the shaft K, having the rods K' K², the gripper-bar I, having the gripper-shaft I³, provided with the arms I⁶ I⁷, and the lever L, and the

fixed cam M, and pivoted latch J, substantially as shown and described.

5. The combination of the reciprocating gripper-bar I and the bent lever N, pivoted to the frame-work and extended over said bar, and adapted to fall by gravity upon the rear end of the table, substantially as shown and described. 20

6. The combination of the swinging frame H', the reciprocating gripper-bar I, the gripper-shaft I³, having the arms I⁶ I⁷, and the bent lever N, substantially as shown and described. 25
